UNITED STATES PATENT OFFICE.

GEORGE E. BERNECKER, OF MILWAUKEE, WISCONSIN.

DESIGN FOR A LIGHT ATTACHMENT FOR SOUND-REPRODUCING MACHINES.

57,574.

Specification for Design.

Patented Apr. 26, 1921.

Application filed August 18, 1920. Serial No. 404,429. Term of patent 14 years.

To all whom it may concern:

Be it known that I, GEORGE E. BERNECKER, a citizen of the United States, residing at Milwaukee, in the county of Milwaukee and State of Wisconsin, have invented a new, original, and ornamental Design for a Light Attachment for Sound-Reproducing Machines, of which the following is a specification, reference being had to the accompanying drawing, forming part thereof.

Figure 1 is a perspective view of a light

attachment for sound reproducing machines, showing my design; and

Fig. 2 is an end view thereof.

I claim:

The ornamental design for a light attachment for sound reproducing machines, as shown.

GEORGE E. BERNECKER.
